UNITED STATES PATENT OFFICE

FRED C. TAMS, OF CHICAGO, ILLINOIS, ASSIGNOR TO GLOBE SPECIALTY COMPANY, OF CHICAGO, ILLINOIS, A CORPORATION OF ILLINOIS

DESIGN FOR A TRAY

Application filed December 24, 1931. Serial No. 42,186. Term of patent 7 years.

To all whom it may concern:

Be it known that I, FRED C. TAMS, a citizen of the United States, residing at Chicago, in the county of Cook and State of Illinois, have invented a new, original, and ornamental Design for a Tray, of which the following is a specification, reference being had to the accompanying drawings, forming a part thereof.

Fig. 1 is a plan view of a tray showing my new design; and

Fig. 2 is a side elevational view of the tray shown in Fig. 1.

I claim:

The ornamental design for a tray, as shown.

FRED C. TAMS.
